UNITED STATES PATENT OFFICE.

ALBERT M. SCHOENBERG, OF SPOKANE, WASHINGTON.

CUT-FILM HOLDER.

1,237,562.

Specification of Letters Patent. Patented Aug. 21, 1917.

Application filed October 16, 1916. Serial No. 125,899.

To all whom it may concern:

Be it known that I, ALBERT M. SCHOENBERG, a citizen of the United States, residing at Spokane, in the county of Spokane and 5 State of Washington, have invented certain new and useful Improvements in Cut-Film Holders, of which the following is a specification.

My invention relates to improvements in 10 cut film holders, and the object of my invention is the provision of a device of this character of cheap, light, simple and efficient construction, which will adequately serve to retain the film in a flat, distended 15 state and prevent curling thereof during the several immersions or baths to which the same is subjected during the processes of fixing, washing, etc.

Broadly, my holder comprises a rigid rec- 20 tangular frame, spring tension members secured to opposite sides of the frame, spring clips carried by the tension members, and means for adjusting the tension members.

The details of construction, combination, 25 and arrangement of parts comprising my complete device, will be hereinafter fully described and claimed, recourse being had to the accompanying drawings forming a part of my application for patent, and in which—

30 Figure 1 is a plan view of the device with a portion of the frame member broken away to show clearly the arrangement, construction, and disposition of the spring film retaining elements.

35 Fig. 2 is an enlarged perspective detail view of one corner of the frame, a section of one of the tensioning springs, and the spring clips carried thereby.

Fig. 3 is an end elevation of a number of 40 my holders indicating the manner of disposing the same in a tank in groups or series, and the staggered arrangement of the tensioning members and the film clips, a feature of my invention.

45 Referring more specifically to the drawings in which like reference characters are used to indicate like parts in the several views, the numeral 1 designates the rectangular frame which is preferably of metal, 50 the sides and ends thereof being formed U-shaped in cross-section or of channel construction to insure strength and rigidity, and thus providing an outer wall 2 and the inwardly extended flange portions 3. Se- 55 cured to said outer wall at opposite ends of

the frame and by means of the rivets 4 are the flat spring tension members 5, said rivets securing the members at points intermediate of their ends so that their end portions may be freely extended under tension 60 by proper adjustment of the buttons 6 which are slidably mounted, in coöperative relation to said end portions of the spring members, in the longitudinal slots 7 in the outer wall 2 of the frame. 65

As clearly shown in Fig. 1 these buttons have the spring engaging knobs 8, shanks 9, and operating heads 10, the latter projecting outwardly from the outer face of the frame in order that they may be conveniently gripped for sliding adjustment of the buttons in the slots. 70

These spring tension members 5 normally extend parallel with and lie flat against the adjacent inner face of the outer wall 2 to 75 which they are secured, and carry at either extremity inwardly extended central spring clip members 11 provided with notches 12 near their free ends and having mounted thereon at opposite sides companion hinged 80 spring clips 13 adapted to engage said notches with their ends to tightly hold the films in place.

In securing the photographic films in the 85 holder the buttons 6 are first moved in their respective slots 7 in the direction of the riveted portion of the springs 5 so that the engaging knobs 8 will force the free end portions of the springs under tension into the position shown at the right of Fig. 1. 90

The films are then secured at their corners by the spring clips, as is also indicated in Fig. 1. Then the buttons 6 are moved along their respective slots 7 until the film is properly outstretched or distended, it being understood that the tension of the springs 5 will serve to accomplish this result when said buttons are so moved as to allow the end portions to return toward their normal position. 95

In order that the frames may nest closely together and hence a maximum number be accommodated in the washing and fixing tanks, every frame in the group or series has its spring tension members 5 offset with 105 respect to the center of their respective retaining walls 2, and are placed in the tanks in alternate order.

As the spring clips 13 project beyond the faces of the frames, this arrangement, 110

shown in Fig. 3, the tank being indicated by the fragments at 14, serves to stagger the corresponding clips of adjacent frames and to provide the necessary clearance between 5 the clips.

The advantages of my holder are obvious. Each frame accommodates two films within a very limited compact space, while the tension exerted by the spring members 5 serves 10 to properly maintain the films outstretched and prevents curling thereof, so that when the frames are inserted in the tank or other container for washing, fixing, etc., they will be held out of contact with or adequately 15 spaced from the adjacent film and its holder.

Having described my invention, I claim:—

1. A cut film holder comprising a frame, tensioning means secured to said frame within the side walls thereof for retaining films 20 or other flexible sheets under tension, and adjusting means for said tensioning means.

2. A cut film holder comprising a frame, spring tension members secured to opposite sides of the frame, film retaining devices 25 carried by said tension members, and adjusting means for the tension members.

3. A cut film holder comprising a frame, spring tension members secured to opposite sides of the frame intermediate of their ends, film retaining devices carried by the free 30 ends of said tension members, and adjusting devices mounted in the frame and adapted

for engagement with and adjustment of the tension members with respect to the frame.

4. A cut film holder comprising a frame, 35 spring tension members fixedly secured to opposite sides of the frame and within the scope thereof, inwardly extended film retaining members carried by said tension members, spring clips mounted in pairs on 40 said retaining members, and adjusting means for adjusting said tension members with respect to said frame.

5. A cut film holder comprising a frame, spring tension members secured to opposite 45 sides of the frame and intermediate of their ends, and within the side walls of the frame, longitudinally slidable adjusting members mounted in the walls of said frame in adjacent relation to said tension members, and 50 film retaining members carried by said tension members.

6. In combination with a receptacle or frame holding device having spaced receiving means for cut film holders, of a cut film 55 holder comprising a frame, spring tension members secured to opposite sides of the frame and within the side walls thereof, and film retaining devices carried by said tension members.

In testimony whereof I affix my signature.

ALBERT M. SCHOENBERG.
